UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed December 22, 1921. Serial No. 524,083.

To all whom it may concern:

Be it known that I, CHARLES L. GOODRUM, a citizen of the United States, residing at New York, in the county of New York, 5 State of New York, have invented certain new and useful Improvements in Telephone-Exchange Systems, of which the following is a full, clear, concise, and exact description.

This invention relates to telephone exchange systems.

The objects of the invention are simplicity of construction, positive action, speedy operation, low first cost, low maintenance charges and flexibility in the arrangement 15 and size of line and trunk groups.

Switching devices having simple movements of slight extent are incorporated in a system of trunking wherein straight forward selection is practiced, where trunk 20 hunting is limited, and where the controlling apparatus is reduced to a minimum through the use of common senders.

A feature of the invention is the adaptation of common senders to trunk lines, each 25 having a plurality of points of egress. Trunk lines of this general character have heretofore necessarily included individual controlling apparatus. By here employing common apparatus, the first cost of the system 30 is greatly reduced, and maintenance is lowered.

Another feature of the invention resides in the adaptation of a marker for identifying the trunk line at any one of its points of egress. The marker is common to the senders which in turn are common to the trunk lines, and the multiplication of elements is thus reduced. Facility of connection is obtained by the use of what may be termed 35 three coordinate selection, each trunk line terminating as it does in a plurality of points of egress and a non-numerical switch being located at each of these points of egress. The line is extended by identifying the particular trunk line at a particular point in one of its points of egress through 40 this three coordinate selection. The first selection is of the particular point of egress; the second selection is of the trunk line in one of the two principal directions of a two coordinate system within the particular point of egress; and the third selection is of a second principal direction of such two coordinate system. The first coordinate 45 selection is made directly in response to the

setting of the sender, and the second and third coordinate selections are made in accordance with the manner in which the trunk line has gained access to the sender, all three selections being controlled directly by the marker. 60

Another feature of the invention resides in the novel method of operation whereby after the selection at any stage is made the connecting apparatus is not operated until 65 controlling apparatus for the next selection stage is seized and made ready for use.

A further feature resides in the provision in a system of the character herein described of a multi-group connector with 70 means for identifying the proper group in accordance with the character of the digit used in selecting the connector, the selection being determined by the value of the digit. 75

Another feature resides in the provision of a system employing selective switches comprising a plurality of link circuits for interconnecting incoming and outgoing lines together with sets of cooperating bars for operating said switches, and means consisting of recording devices for governing the 80 operation of said switches.

The drawings placed together as indicated in Fig. 14 illustrate in a complete dia- 85 grammatic form a telephone system involving the invention. Fig. 1 represents a group of lines with non-numerical or line switch mechanism for connecting the lines when calling to trunks leading to the main groups of lines in the exchange. The sys- 90 tem to be described has a capacity of ten thousand lines and straight forward selection is provided for. Each line may, therefore, be designated by four digits. The outgoing trunks from Fig. 1 lead to mechanism 95 serving the main groups or the different thousands groups and lines. Fig. 2 represents a non-numerical switching mechanism which may be selected in response to the sending of the first digit and the apparatus of this figure therefore represents the first group selecting stage. The trunk lines leading from Fig. 1 to Fig. 2 therefore lead in the direction of the main groups of lines and the operation of the switching appa- 100 ratus of Fig. 2 directs the traffic through such trunk lines to a particular one of said main groups of lines. Fig. 3 in the same manner represents a second group selecting stage and Fig. 4 represents the third group 105 110

selecting stage and the fourth or line selecting stage and corresponds to the final selector stage in modern automatic telephone systems.

- 5 Fig. 5 represents a sender selector, in other words, a non-numerical switching mechanism for connecting the trunks leading from the line switch mechanism of Fig. 1 to the sender which is diagrammatically shown in 10 Fig. 6 so that upon the initiation of a call from one of the lines of Fig. 1, such line will be extended through the line switch of Fig. 1, and the sender selector of Fig. 5 to the sender of Fig. 6. Fig. 6 also includes 15 an associated marker shown in the right-hand portion of the figure for identifying the trunk at any one of its points of egress of which the switching mechanism of Fig. 2 is one. 20 Figs. 7 and 8 are practically the same as Figs. 5 and 6 and perform the same functions in relation to the mechanism of Fig. 3, as the apparatus at Figs. 5 and 6 perform for the circuits of Fig. 2. Figs. 9 and 10 25 represent a sender selector and a sender and marker, respectively, for the final selector of Fig. 4 and correspond very closely to the circuits of Figs. 7 and 8. Fig. 11 illustrates the circuits of apparatus of the trunks between the second group selecting stage and 30 the final selector which functions after the called line has been selected to either return the busy tone to the calling subscriber in case the called line is found to be busy or 35 to ring the called subscriber and complete the connection in case his line is found to be idle. Fig. 12 is a general trunking arrangement and diagrammatically illustrates the interconnection of trunks each of which 40 may be reached through a single switch structure and has a plurality of points of egress. Fig. 13 is a perspective of the mechanical apparatus which may be employed in the circuits and which is shown as a co- 45 ordinate switch.

General description.

- 50 Rectangle 1202 in Fig. 12 represents the connecting mechanism into which lines 0 to 99 enter, and out of which trunks, which for convenience we will number 0 to 9 lead. In a similar manner rectangle 1203 represents the connecting mechanism into which 55 lines 100 to 199 enter and from which trunks 10 to 19 lead. In a fully equipped system of a decimal and 10 per cent trunking basis, there will be ten of these groups of mechanisms serving lines 0 to 999, inclusive, and 60 out of which trunks 0 to 99 lead. Trunks 0 to 99 then go into connecting mechanisms in the same manner as the separate groups of calling lines. For instance, rectangle 1204 represents connecting mechanism into 65 which trunks 0 to 99 enter, and out of which

trunks, which for convenience are numbered 1000 to 1009, lead. These trunks 0 to 99 also enter nine other connecting mechanisms represented here by rectangles 1205, 1206, etc. Thus, a trunk such as one of the trunks 70 0 to 9 has a single switch structure for ingress at 1202 and a plurality of points of egress as at 1204, 1205, 1206, etc. A point of ingress is that point of the trunk into which traffic flows, and the point of egress 75 is that point out of which the traffic flows. Thus the connection being established from the group of lines 0 to 99 will be connected to one of the trunks 0 to 9 at its single point of ingress 1202 and thence extended through 80 one of its points of egress such as 1204.

The calling subscriber in the group 100 to 199 upon initiating a call is connected to a trunk in group 10 to 19. If this calling subscriber desires connection to a subscriber 85 in the first thousands group he will manipulate his calling device to identify the trunk in that one of the ten mechanisms into which this trunk enters which will extend the line to the main group of lines numbered 1000 to 1999. We will assume that rectangle 1204 is the desired one and that by sending one impulse he may identify the trunk to which he has been connected in the group 1204 and thereby select a trunk group 1000 to 1009. 90 There are ten such mechanisms as 1204 into which the trunks of the calling subscribers enter and out of which trunks 1000 to 1099 lead. The trunks 1000 to 1099 each enter ten mechanisms similar to 1204, two of which are here shown as No. 1207 and No. 1215. The subscriber having picked out a line in the first thousands group now wishes to 100 select a line in the first hundreds group of the first thousands group by selecting the first mechanism 1207. By sending one impulse he is then connected to one of the group of trunks represented by 1208. This trunk leads into a connecting mechanism 1214 serving lines 1100 to 1299. By now manipulating his sending device in accordance with the last two digits of the called subscriber's number, he will cause his line to be connected through the mechanism 1214 105 to the particular called line in the group 1100 to 1299.

The particular type of non-numerical switching mechanism used in this disclosure lends itself readily to large groups and as an illustration the connecting device corresponding to the final selector has been shown 110 as a 200 line mechanism. The switching device of Fig. 3 representing the second group selecting stage will automatically differentiate between the even and odd digits 115 so that if the calling subscriber had dialed two in the second instance, and had his connection extended through the switching device 1215 instead of through the switching device 1207, he would still be directed into 120 125 130

the final selecting device 1214, but the switching device 1215 having been selected through the use of an even number of impulses would identify the connection properly in the 200 line switching device 1214. In the manipulation of the dial in accordance with the last two digits, the line in the group 1200 to 1299 will be selected.

For convenience, the general aspects of 10 the trunking scheme have been shown in Fig. 12 in a purely decimal and 10 per cent system. The switching device employed, however, readily lends itself to larger group working and hence it is not at all necessary 15 to lead 100 lines into a group and ten trunks out of the group, but the relationship between the trunks and the lines may be varied according to the demands of traffic in that particular group.

20 In Fig. 1 there are shown six lines in two groups to represent the grouping arrangement in a non-numerical switch similar in function to the well known line switch. The switch contacts of the lines may be 25 coordinately arranged in horizontally and vertically extended groups. The lines of each horizontally extending group may have the same units digit but a different tens digit. The contacts of lines having the same tens 30 digit but different units digits would then be grouped one above the other. In each such vertical group all switch contacts are under the control of the same magnet such as 104. The line relays control primarily the operation 35 of all the switch magnets and the connections from the relays to the magnets may be varied according to any desired plan so that it is not at all necessary that the lines should be numbered or arranged in the manner 40 stated. The arrangement described, however, is typical and is given for the sake of convenience and illustration.

A calling line is identified by two magnets, one having control over the group in one 45 coordinate direction and the other magnet having control over the group in the other coordinate direction. When a line, therefore, initiates a call and causes its line relay to be energized, this line relay will in turn 50 cause the energization of those two magnets representing the intersection of the two coordinates defining this line. A switch of this character is shown in Fig. 13 and functions as follows:

55 Assume that it is desired to establish a connection between the group of conductors 1, 2, 3 and 4 and the group of conductors 5, 6, 7 and 8. Conductor 5 is multiplied at several points to spring wires such as 9 and 10; conductor 6 is multiplied in the same manner to spring wires 11 and 12; conductor 7 is multiplied to spring wires 13 and 14, and conductor 8 is multiplied to spring wires 15 and 16.

65 Associated with the group of conductors

5, 6, 7 and 8 is a magnet 104 which controls an armature 18 to rotate a bar or switching member 19. Secured to this bar and associated with each group of spring wires such as 9, 11, 13 and 15 and 10, 12, 14 and 16, are 70 spring wires 20 and 21, respectively. When the magnet 104 is energized all of the spring wires such as 20 and 21 are moved in a clockwise direction through the rotation of bar 19.

75 Associated with the group of conductors 1, 2, 3 and 4 is a magnet 168 which, through an armature 23, controls a switching member or bar 24. Secured to this bar and associated with each group of conductors similar 80 to the group 5, 6, 7 and 8 are arms such as 25 and 26. After the magnet 104 has become operated and the spring wire 21 has moved to a position above the arm 26, the magnet 168 may be operated whereupon the spring 85 wire 21 will be moved upwardly. Each of the arms such as 25 and 26 contains a notch 27 which is for the purpose of preventing the spring wire 21 from slipping when the magnet 104 is deenergized to return all of the spring wires such as 20 back to their normal positions, leaving only the one 21, in an operated position.

90 Associated with each group of spring wires such as the group 9, 11, 13 and 15 and the group 10, 12, 14 and 16, is a piece of insulating material such as hard rubber or fiber 110 and 109. The spring wires 10, 12, 14 and 16 project through slots cut in the insulating material 109. This insulating 95 piece is so fastened at its lower end that when the spring 21 has been moved in a clockwise direction and the arm 26 has been rotated upwardly, spring 21 will move the insulating piece 109 bodily upward, 100 bringing the spring wires 10, 12, 14 and 16 105 into contact with conductors 1, 2, 3 and 4, respectively.

110 For holding the piece of insulating material 109 in position, two springs 30 and 31 are provided which are threaded through the insulating material and bent over in a manner to locate the piece 109. The spring wire 31 after being threaded through the insulation is also bent upwardly and then 115 outwardly so that when the group of spring wires 10, 12, 14 and 16 is at rest, they will be prevented from moving downwardly a sufficient distance to contact with the conductors of the group 1, 2, 3 and 4.

120 It will be seen from this arrangement that if two magnets 104 and 112 are simultaneously energized and then magnet 168 is energized, a connection will be established from conductor 5 to conductor 1 and thence to conductor 33 and in the same manner conductors 6, 7 and 8 will be connected through conductors 2, 3 and 4 to conductors 34, 35 and 36.

125 The lines of Fig. 1 are assumed to be in 130

the zero thousand group of lines, and for convenience in illustrating, the manner in which the various senders are operated, the group of called lines in Fig. 4 is assumed 5 to be in the 1400 group of lines. For the purpose of fully disclosing the present invention, a connection established by the subscriber on line 0011 to called line 1427 will be described. Such a connection may be 10 traced from the non-numerical switch of Fig. 1, where by means of switching devices 107 and 113, it is connected to trunk 118. Such a trunk line appears in the one non-numerical switch of Fig. 1 and has a plurality of points of egress in switching mechanisms such as is shown in Fig. 2, and which are reached through the multiple taps 222.

The device herein termed a marker employs a multiple contact relay such as that 20 shown, described and claimed in the pending application of Forsberg, Serial No. 482,106, filed July 2, 1921. This marker is shown in the right-hand portion of Fig. 6, and functions to identify the particular 25 trunk employed in one of the plurality of points of egress, and thus forms a means for manipulating what may be termed a three-coordinate system. The selection of a particular row of contacts by either magnet 30 610, 611, 612, etc., determines the first coordinate selection. The selection of a particular magnet 606, 607, etc. determines the second coordinate selection and the selection 35 of particular contacts in the row selected by these magnets, as determined by the manipulation of the counting relays of the sender, determines the third coordinate selection. By means of these three coordinate selections the trunk 118 may be 40 identified in any one of its points of egress, and its identification in the switching mechanism of Fig. 2 will be hereinafter fully described.

When the subscriber at station 100 on 45 line 0011 removes his receiver from its switchhook, line relay 102 will be energized. This will immediately cause the energization of magnet 104 and magnet 104 will in turn cause the energization of magnet 112, 50 which will prepare for operation, the switching devices shown vertically above them. The energization of magnet 112 will result in the energization of two similar magnets in the sender selector of Fig. 5, 55 namely, magnets 504 and 512. These two magnets likewise prepare for operation the switching devices shown vertically above them. Upon the operation of magnet 512, the impulse relay of the sender and thereafter the holding relay of the sender, are 60 energized, whereupon the magnet 503 will become energized and operate two of the switching devices prepared for operation by magnets 504 and 512. These switching 65 devices are numbered on the drawings 509

and 515, respectively. Through the operation of the holding relay of the sender, magnet 503 will be locked in its energized position. When the switching devices 515 and 509 have been operated, a ground connection 70 from the holding relay of the sender will be extended back over the trunk 118, whereupon the magnet 103 will become energized and operate the switching devices 107 and 113. Thus it will be seen that the 75 complete operation of the switching device of Fig. 1 depends upon the successful connection of a sender to the trunk which will be used. If no sender is available at this time, the three magnets 104, 112 and 504 80 will remain operated under the control of the calling subscriber's line relay, and will remain in this condition until a sender becomes available and is seized through the energization of the magnet such as 512. 85 This feature of delaying the action of the switching mechanism at any one of the selecting stages until a sender is actually available and connected to the trunk will be observed throughout the following detailed 90 description of the operation. When the sender of Fig. 6 is seized and the holding relay thereat is operated, the ground connection will be extended back over trunk 118 as described to cause the operation of 95 magnet 103. Magnet 103 will lock to the ground connection controlled by the holding relay of the sender. Upon the operation of this magnet, magnets 104 and 112 100 will be deenergized, and in turn magnets 504 and 512 will be deenergized. The subscriber's line 0011 is now extended to the sender and has control over the counting relays so that upon the manipulation of the impulse transmitter at substation 100, the 105 sender will be operated.

The connector switch shown in Fig. 4 is designed with a 200-line capacity, the subscribers' lines terminating therein being divided for that purpose into ten groups of 110 twenty lines each, each group of twenty lines being further divided into two sections of ten lines each. All lines in the group of 200 having the same units digit are grouped in one subgroup of twenty lines. 115 Thus, as shown, lines 1417, 1427, 1437, etc. having the units digit 7 comprise one subgroup in one coordinate direction and likewise lines 1416, 1426, 1436, etc. having the units digit 6 comprise another similar subgroup. Selection of subgroups in the units coordinate direction is effected through the selection and operation of a units magnet such as 403 under the control of the units 120 contacts of either one of the markers 1006 or 1007 in Fig. 10.

Tens selection in the other coordinate direction of the connector switch is effected through the selection and operation of tens magnets such as shown at 404, 405 and 406. 130

Since each subgroup of lines comprises twenty lines, two sections of ten magnets each are provided. Each units subgroup of lines thus includes lines having the same 5 units and tens digit but different hundreds digits. Thus, under the assumption that the connector switch, Fig. 4, serves the group of lines including lines 1300 to 1499, inclusive, the subgroup having the units digit 10 7 would include lines 1317, 1327, 1337, etc., as well as lines 1417, 1427, 1437, etc. It is thus necessary to further divide each units 15 sub-group of twenty lines in the other coordinate direction of the switch into two sections as hereinbefore noted, the sections being characterized by the hundreds digits, being odd or even, lines 1317, 1327, 1337 thus constituting one such section and lines 1417, 1427 and 1437 the other section. Magnet 20 404 then serves in the selection of all lines having the even hundreds digit 4 and the tens digit 1, and similarly magnet 405 serves in the selection of all lines having the even hundreds digit 4 and the tens digit 25 2. For the selection of lines having the odd hundreds digit 3 and tens digits 1 to 0, inclusive, a second set of magnets similar to magnets 404, 405 and 406 is provided.

When the hundreds digit is even, the 30 marker 1007 is operated and marks a units magnet such as 403 and a tens magnet of the even hundreds section such as 404, 405 or 406 for subsequent operation. If the hundreds digit is odd the marker 1006 is 35 operated and marks a units magnet and a tens magnet of the odd hundreds section (not shown) over conductors such as 1076, 1077 and 1078 of Fig. 10 for subsequent operation.

40 Having thus given a general description of the action of the apparatus in response to the initiation of a call, the circuits will be described in detail.

45 *Detail description of circuit operation.*

When the subscriber at station 100 removes his receiver from the switchhook, a circuit will be established from battery, right-hand winding of line relay 102, back 50 contact and inner left-hand armature of cutoff relay 101, over the loop of the calling substation 100 the outer left-hand armature and back contact of cutoff relay 101, the left-hand winding of line relay 102 to ground. Line 55 relay 102 becomes energized in this circuit and establishes the following connection for the energization of magnet 104: from ground, left-hand armature and back contact of magnet 103, conductor 150, front contact and inner armature of line relay 102, conductor 151, winding of magnet 104 to battery. Magnet 104 becomes energized and prepares for operation switching devices 60 107 to 110, inclusive. Upon its energization, magnet 104 removes the battery connection 65 from magnets 105 to 106 so as to prevent the possibility of a double connection. A circuit is also established at this time from ground, the inner right-hand armature and front contact of magnet 104, conductor 152, 70 armature and front contact of relay 119 (assuming trunk 117 to be busy at this time) armature and back contact of relay 120, winding of magnet 112 to battery (assuming trunk 118 to be idle at this time). 75

Magnet 112 becoming energized, prepares for operation switching devices 113 to 116, inclusive. A circuit is now established from ground, the left-hand armature and front contact of magnet 112, conductor 153, conductor 250, conductor 550, winding of magnet 504, to battery and ground. Magnet 504 prepares for operation switching devices 507 to 510, inclusive, and removes the battery connection from the windings of 80 magnets 505 and 506 to prevent the possibility of a double connection. A circuit is now established from ground, the front contact and left-hand armature of magnet 504, conductor 552, armature and front contact of relay 519, (assuming trunk 517 to be busy at this time) armature and back contact of relay 520, winding of magnet 512 to battery and ground. Magnet 512 becomes 85 energized in this circuit and prepares for 90 operation switching devices 513 to 516, inclusive. Upon its energization magnet 512 establishes a connection from ground, left-hand armature and first front contact, conductor 553, conductor 554, conductor 254, conductor 154, inner right-hand armature and front contact of magnet 112, conductor 155, conductor 255, conductor 555, normal contacts of the inner armature of magnet 503, winding of magnet 503 to battery and 95 ground. Magnet 503 becomes energized in 100 this circuit and operates switching devices 509 and 515. Through the energization of magnet 512 a circuit is also established from ground, left-hand armature and second front 105 contact of magnet 512, conductor 551, conductor 600, winding of impulse relay 601, to battery and ground. Relay 601 becomes energized in this circuit and establishes a circuit from ground, armature and front 110 contact of relay 601, winding of slow-to-release holding relay 603 to battery. Holding relay 603 attracts its armatures and establishes a connection from ground, left-hand armature and front contact of relay 603, conductor 604, conductor 556, through the corresponding contacts of switching device 515, conductor 557, inner armature and alternate contact of magnet 503, winding 115 of magnet 503, to battery, whereby magnet 503 remains locked in its energized position. Grounded conductor 557 is also connected through the corresponding contacts of switching device 509 to conductor 558, conductor 120 258, normal contacts of the right-hand armature 125 and inner armature of line relay 102, conductor 151, winding of magnet 104 to battery. Magnet 104 becomes energized and prepares for operation switching devices 107 to 110, inclusive. Upon its energization, magnet 104 removes the battery connection 130

ture of relay 201, conductor 251, conductor 156, outer right-hand armature and front contact of magnet 112, conductor 157, left-hand armature and front contact of magnet 5 104, conductor 158, outer armature and front contact of line relay 102, conductor 159, normal contacts of the inner right-hand armature of magnet 103, winding of magnet 103, to battery and ground. Magnet 103 10 becomes energized in this circuit and causes the operation of switching devices 107 and 113, whereupon grounded conductor 156 is connected through the corresponding contacts of switching device 113 to conductor 15 160 and thence through the inner right-hand armature and alternate contact of magnet 103, winding of magnet 103 to battery and ground, to maintain this magnet locked in its energized position. Grounded conductor 20 160 is also extended through the corresponding contacts of switching device 107 to conductor 161, and thence through the winding of cutoff relay 101, which becomes energized and cuts off the line relay from the 25 control by the substation 100. The ground potential on conductor 161 is also extended through the corresponding multiple tap in the group 122 to mark this line as busy in the connector switch in which it appears, 30 the taps 122 being connected to corresponding taps in the proper hundreds group connector.

Through the operation of magnet 103 and cutoff relay 101, the original energizing circuit for magnet 104 is opened, and this magnet becomes deenergized. Thereupon, the energizing circuit for magnet 112 is opened, and this magnet in turn becomes deenergized. Upon its deenergization, grounded 35 conductor 156 is connected through the outer right-hand armature and back contact of magnet 112, through the winding of relay 120 to battery, so that the starter wire 152 may be extended to the next idle trunk. The 40 deenergization of magnet 112 opens the original energizing circuits for magnets 504 and 503. Magnet 504 becomes deenergized, but magnet 503 remains operated due to the locking circuit which has been established. 45 Upon the deenergization of magnet 504, the original energizing circuit for magnet 512 is opened and it becomes deenergized. Upon the retraction of the armatures of magnet 512, the original energizing circuit for the 50 impulse relay 601 is opened, but a substitute circuit has previously been established which may be traced from battery, winding of impulse relay 601, conductor 600, conductor 551, corresponding contacts of switching device 515, conductor 559, corresponding contacts of switching device 509, conductor 560, conductor 260, outer left-hand armature and back contact of relay 201, conductor 253, conductor 162, corresponding contacts of 55 switching device 113, conductor 163, corre-

sponding contacts of switching device 107, conductor 164, through the loop substation 100, conductor 165, corresponding contacts of switching device 107, conductor 166, corresponding contacts of switching device 113, 70 conductor 167, conductor 256, back contact and inner left-hand armature of relay 201 to ground. Through this circuit the subscriber at station 100 has complete control over the sender of Fig. 6. Also, through the deenergization of magnet 512 the grounded conductor 556 is connected through the right-hand armature and back contact of magnet 512, the winding of relay 520, to battery and ground, whereupon this relay 75 becomes energized and extends the starter wire 552 to the next idle trunk.

All of this operation has taken but a fraction of a second and the apparatus which has responded to the initiation of the call at 80 substation 100 is now in a stable condition awaiting the manipulation of the impulse transmitter.

It should be noted at this point that if another call should now be initiated, say 85 by line 0012, that magnet 104 will again be operated, but will in no way affect the switching device 107 since this is locked against operation by the magnet 103. At this time switching devices 108, 109 and 110 will be 90 prepared for operation, and when the rest of the apparatus is in condition, magnet 169 will become energized (assuming that magnet 168 is energized in a connection extending line 0022 over the link 170 to trunk 117). 100 The energization of magnet 169 in the present case will extend line 0012 over link 171 to the next idle trunk similar to trunks 117 and 118. It will thus be seen that every 105 idle link circuit, such as 121, 170 and 171, is available, and very little apparatus other than that actually used in the connection is rendered incapable of use during the existence of a connection. It is to be particularly noted that a magnet such as 104 may 110 be used to successively establish a plurality of connections.

Thousands selection.

115

Through the use of the sender selector and the non-numerical switch of Fig. 1, a small number of senders, only so many as the traffic requires, may be made common to a large number of calling lines. Fig. 6 120 represents two such senders, the broken line rectangle to the left being a duplicate of the organization of relays forming the sender which is located in the center of this figure. Since it has been assumed that the number 125 of the called substation is to be 1427, the subscriber on line 0011 will manipulate his impulse sending device (not shown) at substation 100 to send a single impulse. Such an impulse is in the form of a single 130

short interruption of the subscriber's line circuit, and controls impulse relay 601 by causing it to retract its armature for an instant. During the retraction of this armature, the energizing circuit for holding relay 603 is opened, but this relay being of the slow releasing type, does not respond. Therefore, a circuit is established from ground, armature and back contact of impulse relay 601, right-hand armature and front contact of holding relay 603, winding of relay 608 to battery and ground, and in parallel with the winding of relay 608, through the lower armature and back contact of relay 609, winding of relay 613 to battery and ground. Relays 608 and 613 respond to the establishment of this connection and attract their armatures. Relay 613 thereupon establishes a circuit from ground, the left-hand armature and front contact of relay 603, conductor 604, front contact and upper armature of relay 613, winding of relay 609, winding of relay 613 to battery and ground. Relay 609, however, does not become energized at this time due to the ground connection from its own lower armature and front contact to the connection between the windings of relays 609 and 613. At the end of the interruption of the circuit of relay 601, the armature of relay 601 is again attracted and the original circuit for the energization of relay 613 is broken, but now the substitute circuit through the winding of relay 609 becomes effective and relay 609 also becomes energized. Succeeding impulses would in a similar manner cause the energization of successive pairs of counting relays 617, 628, etc., there being ten pairs of such relays provided for each sender. Relay 608, being of the slow releasing type, does not immediately become deenergized, so that if more impulses were to be sent, this relay would remain energized until after the final impulse had been recorded. There being but one impulse in this train, relay 608 now becomes deenergized, whereupon a circuit is established from ground, armature and front contact of relay 601, front contact and outermost upper armature of relay 609, armature and back contact of relay 608, winding of relay 614, to battery. Through its innermost left-hand armature, relay 614 cuts off the battery connection to similar relays in other senders corresponding to that shown in the sender of Fig. 6, one of which is designated 620 in the broken line rectangle at the left of Fig. 6. Relay 614 now establishes a circuit from ground, inner right-hand armature and front contact of relay 614, conductor 615, conductor 561, corresponding contacts of switching device 515, conductor 562, corresponding contacts of switching device 509, conductor 563, conductor 616, magnet 610, to battery and ground. Through the energization of magnet 610 a circuit is established from ground, front contact and middle left-hand armature of relay 614, inner upper armature and front contact of relay 609, upper armature and back contact of relay 617, conductor 618, corresponding contacts of switching device 619 (controlled by magnet 610), conductor 621, conductor 564, conductor 257, winding of magnet 204, to battery and ground. Magnet 204 becomes energized in this circuit and prepares for operation switching devices 207 to 210, inclusive. Upon its energization magnet 204 establishes a connection from ground, front contact and left-hand armature of magnet 204, conductor 258, armature and front contact of relay 219, (assuming that trunk 217 is at the time busy), the armature and back contact of relay 220, (assuming trunk 218 to be idle at this time), winding of magnet 212, to battery and ground. Magnet 212 becomes energized in this circuit and prepares for operation switching devices 213 to 216, inclusive. Upon its energization magnet 212 establishes a connection from ground, left-hand armature and front contact of magnet 212, conductor 259, conductor 350, conductor 750, winding of magnet 704, to battery and ground. Magnet 704 becomes energized in this circuit and prepares for operation switching devices 707, 708, 709 and 710. A circuit is now established from ground, front contact and left-hand armature of magnet 704, conductor 752, armature and front contact of relay 719, (assuming trunk 717 to be busy at this time), armature and back contact of relay 720, winding of magnet 712 to battery and ground (assuming trunk 718 to be idle at this time). Magnet 712 becomes energized in this circuit and prepares for operation switching devices 713, 714, 715 and 716. Magnet 712 also establishes a circuit from ground, left-hand armature and first front contact, conductor 753, conductor 754, conductor 354, conductor 260, inner right-hand armature and front contact of magnet 212, conductor 261, conductor 355, conductor 755, normal contacts of the inner armature of magnet 703, winding of magnet 703 to battery and ground. Magnet 703 becomes energized in this circuit. A circuit is also established from ground, left-hand armature and second front contact of magnet 712, conductor 751, conductor 800, winding of impulse relay 801 to battery and ground. Impulse relay 801 becomes energized in this circuit and attracts its armature establishing a circuit for slow releasing holding relay 803 over a circuit including ground, armature and front contact of relay 801, conductor 802, winding of relay 803 to battery and ground. Relay 803 in attracting its armatures establishes a circuit from ground, left-hand armature and front contact of relay 803, con-

ductor 804, conductor 756, corresponding contacts of switching device 715 (which was operated by the energization of magnet 703), conductor 757, inner armature and alternate contact of magnet 703, winding of magnet 703 to battery and ground. Magnet 703 is locked in this circuit. The grounded conductor 757 is also connected through the corresponding contacts of switching device 709 (also operated upon the energization of magnet 703), conductor 758, conductor 358, normal contacts of the right-hand armature of relay 301, conductor 351, conductor 262, outermost right-hand armature and front contact of magnet 212, conductor 263, conductor 565, conductor 622, armature and front contact of magnet 610, conductor 623, outermost right-hand armature and front contact of relay 614, conductor 624 conductor 566, corresponding contacts of switching device 515, conductor 567, conductor 568, conductor 605, winding of magnet 607 to battery and ground. Magnet 607 becomes energized in this circuit and operates switching device 625, whereupon a circuit is established from ground, armature and front contact of relay 601, conductor 602, conductor 626, front contact and outermost left-hand armature of relay 614, conductor 627, lower armature and front contact of relay 613, lower armature and back contact of relay 628, conductor 629, corresponding contacts of switching device 625, conductor 630, conductor 569, conductor 264, normal contacts of the inner right-hand armature of magnet 203 to battery and ground. Magnet 203 becomes energized in this circuit and causes the operation of switching devices 209 and 215, whereupon the grounded conductor 262 is connected through the corresponding contacts of switching device 215, to conductor 265, the inner armature and alternate contact of magnet 203, winding of magnet 203, to battery and ground. Magnet 203 is locked in this circuit. Grounded conductor 265 is also connected through the corresponding contacts of switching device 209 to conductor 266, winding of relay 201, to battery and ground. Through the energization of this cutoff relay the connection between the subscriber's substation 100 and the impulse relay of the sender of Fig. 6 is severed, and the grounded conductor 266 is connected to conductor 251.

Impulse relay 601 now becomes deenergized and immediately establishes a circuit for the energization of relay 608 which opens the circuit of relay 614. Relay 614 becoming deenergized opens the circuit of magnets 607 and 610 whereby switching devices 625 and 619 are returned to normal and thereby open the original energizing circuits of magnets 204 and 203. Magnet 204 becoming deenergized opens the ener-

gizing circuit for magnet 212, which in turn, opens the energizing circuit for magnet 704 and this, in turn, opens the energizing circuit for magnet 712. The substation 100 is now in control of the impulse relay 801 in a manner similar to that heretofore described. After a short interval slow releasing relay 603 becomes deenergized and removes the ground from conductor 604 which allows the counting relays 609 and 613 to become deenergized and thereby restores the sender to its normal condition. Ground being removed from conductor 604 allows magnet 503 to become deenergized whereupon the sender selector of Fig. 5 is returned to normal. Upon the deenergization of magnet 212 grounded conductor 262 is connected through the outer right-hand armature and back contact of magnet 212, winding of relay 220 to battery and ground, so that upon the next call through the switching device of Fig. 2 when conductor 258 is grounded by the operation of any of the magnets 204, 205 or 206, the next idle trunk will be used. All of this operation following the sending of the single impulse from substation 100 has taken but a fraction of a second and the apparatus is now in a stable condition awaiting the sending of the next series of impulses.

It should be noted here that the sender selector of Fig. 5 distributes calls incoming from a large plurality of lines to a relatively small number of senders as shown in Fig. 6. It should also be noted that the marker comprising switching devices operated by magnets 606, 607, 610, 611 and 612 is common to a plurality of senders such as that shown in the central portion of Fig. 6 and the one indicated in the broken line rectangle 620. The sender is attached to the line upon the initiation of the call and remains so connected until after the series of impulses has been received and the marker correspondingly operated. The marker, however, does not come into use until after the impulses have been recorded and thus is in use for only a very short interval. If the two senders of Fig. 6 are both in use at the same time and a series of impulses is being recorded on the counting relays of both almost simultaneously and those in the sender shown in full are recorded just a fraction of a second before those being recorded in sender 620, then the control of the common marker by sender 620 will be held up for an instant due to the opening of the circuit at the inner left-hand armature and back contact of relay 614. As soon as the control of the marker by the sender shown in full has become effective, relay 614 will become deenergized as hereinbefore described and the corresponding relay in sender 620 will thereupon become energized and it will become effective to control the marker. If

- the impulses being received by sender 620 are completely recorded a fraction of a second before those in the sender shown in full, then the sender 620 will function immediately, but when the impulses being recorded in the sender shown in full are completely recorded, relay 614 will become energized and cut off the corresponding relay in sender 620, and if this should happen before sender 620 has become effective to control the marker, then it is held up as before described and does not become effective until after relay 614 has become de-energized. Such an action, however, will rarely occur, and if it does occur, will be by the merest chance and even then no harm will result, for the functioning of sender 620 will only be delayed for an extremely short period of time.
- 20 If the calling subscriber had sent a series of more than one impulse, say a series of three impulses, then conductors 631 and 632 would have been affected instead of conductors 621 and 630, respectively, and another switching device similar to that shown in Fig. 2 would have been actuated and the trunk 118 instead of being extended by means of switching devices 207 and 215 would have been extended through the multiple taps 222 through some other switching device leading to the third thousands group of lines.

Hundreds selection.

- 35 In accordance with our assumption, the calling subscriber will now send a series of four impulses over a circuit which may be traced from battery, through the winding of relay 801, conductors 800 and 751, corresponding contacts of switching device 715, conductor 759, corresponding contacts of switching device 709, conductors 760 and 360, the outer left-hand armature and back contact of relay 301, conductors 372 and 272, corresponding contacts of switching device 215, conductor 267, corresponding contacts of switching device 209, conductor 253, thence as previously traced over the subscriber's line loop, conductor 256, corresponding contacts of switching device 209, conductor 268, corresponding contacts of switching device 215, conductors 273 and 373, to ground at the inner left-hand armature and back contact of relay 301.
- 55 Upon the occurrence of the first impulse, a circuit will be established from ground, armature and back contact of relay 801, right-hand armature and front contact of relay 803, winding of relay 808, to battery and ground. This ground connection will also be extended to the lower armature of relay 809, winding of relay 813 to battery and ground. At the end of this impulse when the armature of relay 801 is again attracted relay 809 will be included in a circuit with relay 813, this circuit being traced from ground, left-hand armature and front contact of relay 803, conductor 804, front contact and upper armature of relay 813, winding of relay 809, winding of relay 813 to battery and ground. Upon the next impulse the ground connection at the armature of relay 801 will be extended through the lower armature and front contact of relay 809, the lower armature and back contact of relay 817, winding of relay 828, to battery and ground. Relay 828 will become energized in this circuit, and upon the end of this impulse relay 817, will be included in a circuit in series with it. In this manner at the end of the fourth impulse, relays 832 and 833 will become energized. Ten pair of counting relays similar to the relays shown are provided for registering a maximum of ten impulses. Shortly thereafter, relay 808 will become deenergized and retract its armature whereupon a circuit will be established from ground, armature and front contact of relay 801, conductor 802, front contact and outermost upper armature of relay 809, armature and back contact of relay 808, winding of relay 814 to battery and ground. Relay 814 will become energized in this circuit whereupon a circuit will be established from ground, inner right-hand armature and front contact of relay 814, conductor 815, conductor 761 through the corresponding contacts of switching device 715, conductor 762, corresponding contacts of switching device 709, conductor 763, conductor 816, winding of magnet 810 to battery and ground. Magnet 810 will operate the switching device 819. A circuit will now be established from ground, middle left-hand armature and front contact of relay 814, inner upper armature and front contact of relay 809, upper armature and front contact of relay 817, upper armature and front contact of relay 834, upper armature and contact of relay 833, upper armature and back contact of relay 835, conductor 818, corresponding contacts of switching device 819, conductor 821, conductor 764, conductor 357, winding of magnet 304 to battery and ground. Magnet 304 becomes energized and establishes a circuit from ground, front contact and left-hand armature of magnet 304, conductor 358, right-hand armature and back contact of relay 334, conductor 337, right-hand armature and front contact of relay 319 (assuming trunk 317 to be busy), right-hand armature and back contact of relay 320, right-hand winding of relay 340, conductor 338, winding of magnet 312 to battery and ground. Magnet 312 is energized in this circuit and establishes a connection from ground, left-hand armature and front contact of magnet 312, conductor 120

- 359, conductor 450, conductor 950, winding of magnet 904 to battery and ground. Magnet 904 becomes energized in this circuit and establishes a circuit from ground, 5 front contact and left-hand armature of magnet 904, conductor 952, armature and front contact of relay 919, (assuming trunk 917 to be busy at this time), armature and back contact of relay 920, winding of magnet 912, to battery and ground. Magnet 912 prepares for operating switching devices 913, 914, 915 and 916. At the same time this magnet establishes a circuit from ground, left-hand armature and second 10 front contact of magnet 912, conductor 951, conductor 1000, winding of impulse relay 1001 to battery and ground. Impulse relay 1001 becomes energized in this circuit and establishes a circuit from ground, armature and front contact of relay 1001, conductor 1002, winding of relay 1003 to battery and ground. Relay 1003 attracts its armatures and establishes a circuit from ground, front contact and left-hand armature of relay 1003, conductor 1004 to conductor 956. Magnet 912 also establishes a circuit from ground, left-hand armature and first front contact, conductor 953, conductor 454, conductor 360, inner right-hand 15 armature and front contact of magnet 312, conductor 361, conductor 455, conductor 955, normal contacts of the inner, right-hand armature of magnet 903 to battery and ground. Magnet 903 becomes energized 20 in this circuit and actuates switching mechanisms 909 and 915. The grounded conductor 956 is now extended through the corresponding contacts of switching device 915 to conductor 957, thence through the 25 inner right-hand armature and alternate contact of magnet 903, winding of magnet 903 to battery and ground, whereby magnet 903 is locked in its energized position. The grounded conductor 957 is now extended 30 through the corresponding contacts of switching device 909, conductor 958, conductor 458, conductor 1100, back contacts of the right-hand armature of relay 1101, conductor 1102, conductor 440, conductor 362, front contact and left-hand armature of relay 340 to battery and ground, whereby 35 relay 340 is locked in its energized position. Grounded conductor 1100 is also connected through the right-hand armature of relay 1101 to conductor 1103, conductor 441, conductor 332, outer right-hand armature and front contact of magnet 312, conductor 363, conductor 765, conductor 822, armature and front contact of magnet 810, conductor 46 40 conductor 823, outermost right-hand armature and front contact of relay 814, conductor 824, conductor 766, corresponding contacts of switching device 715, conductor 767, conductor 768, conductor 805, winding of magnet 807 to battery and ground. Magnet 807 becomes 45 energized in this circuit and actuates switching mechanism 825. A circuit is now established from ground, armature and front contact of relay 801, conductor 802, and outermost left-hand armature and contact 70 of relay 814, conductor 827, lower armature and front contact of relay 827, lower armature and front contact of relay 828, lower armature and front contact of relay 837, lower armature and front contact of relay 75 832, lower armature and back contact of relay 836, conductor 829, corresponding contacts of switching device 825, conductor 830, conductor 768, conductor 364, normal contacts of the inner right-hand armature 80 of magnet 303, winding of magnet 303 to battery and ground. Magnet 303 becomes energized in this circuit and actuates switching mechanisms 309 and 315. The grounded conductor 362 is now extended through the corresponding contacts of switching device 315 to conductor 365, inner right-hand armature and alternate contact of magnet 303, winding of magnet 303 to battery and ground whereby magnet 303 is locked in 90 its energized position.
- The grounded conductor 365 is now extended through the corresponding contacts of switching device 309, through conductor 366, and thence through the winding of 95 relay 301 to battery and ground. Relay 301 becomes energized in this circuit and extends the grounded conductor 366 to conductor 351. Relay 301 severs the connection between the calling subscriber and impulse relay 801, whereupon this relay retracts its armature, and operating relay 808 in the manner heretofore described opens the circuit of relay 814 to release the magnets 807 and 810 of the marker. Relay 100 803 becomes deenergized after a short interval and removes the ground from conductor 804, whereupon magnet 703 becomes deenergized and releases the connection between trunk 218 and the sender of Fig. 8. 105 Upon the deenergization of magnets 807 and 810, magnets 304 and 312 become deenergized. The deenergization of magnet 312 extends the grounded conductor 332 through the outermost right-hand armature and back contact of magnet 312, through the winding of relay 320 to battery and ground so that this relay becomes energized and extends the starter wire on to the next idle 110 trunk.
- Upon the deenergization of magnet 312, magnets 904 and 912 become deenergized in a manner similar to that heretofore described. The calling subscriber now has control of the impulse relay 1001 over a 115 circuit from ground, normal contacts of the outermost left-hand armature of relay 1101, conductor 1104, conductors 476 and 376, corresponding contacts of switching device 315, conductor 375, corresponding contacts 120 125 130

of switching device 309, thence over the loop of the calling substation 100, as previously traced, corresponding contacts of switching device 309, conductor 374, 5 corresponding contacts of switching device 315, conductors 377 and 477, conductor 1105, inner left-hand armature and back contact of relay 1101, conductor 1106, conductor 460, conductor 960, corresponding contacts of 10 switching device 909, conductor 959, corresponding contacts of switching device 915, conductor 951, conductor 1000, winding of impulse relay 1001 to battery and ground. Impulse relay 1001 is therefore under direct control of the calling substation and will respond to the impulses transmitted therefrom. The apparatus is now in a stable condition awaiting the sending of the last 15 two series of impulses to designate the tens and units digits of the called line.

It should be noted at this point that if the second digit had been odd instead of even, that a somewhat different circuit condition would have been established. For instance, if the subscriber, instead of dialing four in the second instance, had dialed three, then conductor 831 would have been affected instead of conductor 821. Conductor 831 extending as it does through conductor 731 to 20 conductor 381, winding of relay 334 to battery and ground, would have energized this latter relay. Relay 334 becoming energized attracts its armatures and extends the grounded conductor 331 through the left-hand armature and the front contact of relay 334, winding of magnet 304. Thus the same magnet as before would have become energized, but in addition, relay 334 will have attracted its armature. Upon the energization of magnet 304 in this latter case, a circuit will be established from ground, front contact and left-hand armature of the magnet 304, right-hand armature and front contact of relay 334 to conductor 330, thence 25 through the left-hand armature and front contact of relay 319 (assuming trunk 317 to be at the time busy), the left-hand armature and back contact of relay 320, through winding of magnet 312. It will be noticed in this 30 case that relay 340 does not become energized and the purpose of this will be explained more fully hereinafter.

55 Tens and units selection.

The calling subscriber having transmitted the series of four impulses and thereby caused the trunk 218 to be extended through the switching device shown in Fig. 3 to the 60 trunk 318 and further caused the actuation of the sender selector of Fig. 9 to attach the sender of Fig. 10 to his line will now proceed to transmit the last two series of impulses for picking out line 27 in the 14 hundreds group of lines. The calling sub-

scriber having control over impulse relay 1001 as described causes this relay to retract its armature two times in quick succession in sending a series of impulses representing the digit 2. Upon the first retraction of its 70 armature by relay 1001, a circuit is established from ground, armature and back contact of relay 1001, right-hand armature and front contact of relay 1003, winding of slow releasing relay 1008, conductor 1042, lower 75 armature and back contact of relay 1009, winding of relay 1013, to battery and ground. Relays 1013 and 1008 become energized in this circuit. At the end of this impulse, when the armature of relay 1001 is attracted, 80 a circuit is established from ground, front contact and left-hand armature of relay 1003, conductor 1004, outer left-hand armature and back contact of relay 1040, conductor 1041, outermost upper armature and front contact 85 of relay 1013, winding of relay 1009, winding of relay 1013 to battery and ground whereupon relay 1009 becomes energized and extends the impulse wire 1042 on to the armature of relay 1017. Relay 1008 has its circuit opened at this time, but being slow to release does not retract its armatures unless its circuit is open over more than a predetermined length of time. Upon the second 90 retraction of its armature, relay 1001 establishes a circuit over conductor 1042, the lower armature and front contact of relay 1009 to the armature and back contact of relay 1017, through the winding of relay 1028 to battery and ground. At the end of this impulse, 95 relay 1017 becomes energized and shortly thereafter relay 1008 retracts its armatures. Thereupon a circuit is established from ground, front contact and left-hand armature of relay 1003, conductor 1004, inner left-hand armature and back contact of relay 1040, back contact and left-hand armature of relay 1008, conductor 1043, through the upper armatures 100 and back contacts of relays 1044 and 1045, conductor 1046, right-hand winding of relay 1047, conductor 1048, upper armature and front contact of relay 1017, conductor 1049, winding of relay 1050 to battery and ground. Relays 1047 and 1050 become energized in 105 110 this circuit.

At this point the action of relays 1047 and 1050 and 1051 will be briefly described. Relay 1051 is connected to the front contacts of relays 1009 and 1045, these two 115 latter relays representing impulse trains of one and six impulses, respectively. In a like manner, relay 1050 is connected to the front contacts of relays 1017 and 1044, these latter two relays representing trains of two and seven impulses, respectively. There are other relays similar to relays 1050 and 1051 provided, which are responsive respectively to trains of three and eight impulses, to 120 trains of four and nine impulses, and to 125 130

trains of five and ten impulses, respectively. Relay 1047 is included in the circuit previously traced whenever relays 1009 and 1017 and corresponding relays (not shown) 5 representing trains of three, four and five impulses are actuated. Whenever relays 1044 and 1045 and similar relays (not shown) representing trains of eight, nine and ten impulses are actuated, relay 1047 is 10 not included in the circuit. Therefore, when any of the digits 1 to 5 are dialed, conductor 1052 becomes effective through the right-hand armature and front contact of relay 1047 and whenever digits 6 15 to 0, inclusive, are dialed, conductor 1053 becomes effective through the right-hand armature and back contact of relay 1047. In the present instance, two impulses have 20 been transmitted. Therefore, relay 1017 has been energized with the consequent energization of relays 1047 and 1050 as previously described. Relay 1047 locks 25 through its front contact and left-hand armature to the grounded conductor 1004, which conductor is also extended through the upper armature and two front contacts 30 of relay 1050 to lock 1050 in its energized position. Relay 1040 now energizes over a circuit extending through its winding and the upper armature and front contact of relay 1050 to grounded conductor 1004. Thereupon the ground is removed from 35 conductor 1041 and the counting relays are returned to normal. The grounded conductor 1004 is now extended through the inner left-hand armature and front contact of relay 1040, conductor 1054, back contacts and inner upper armatures of the 40 lower counting relays, conductor 1055, winding of relay 1056 to battery and ground. Relay 1056 closes a circuit from ground, 45 armature and front contact of relay 1001, conductor 1002, back contact and right-hand armature of relay 1008, front contact and left-hand armature of relay 1056 to conductor 1057. The apparatus now remains in this condition until the subscriber sends the last series of impulses.

In accordance with our assumption the 50 subscriber will now send a series of seven impulses, whereupon the counting relays will be actuated as heretofore described and at the end of this series, relay 1059 will be actuated. The operated counting 55 relays lock over conductor 1041, the outer right-hand armature and front contact of relay 1056 to grounded conductor 1004. A circuit is now established from ground at the armature and front contact of relay 1001, conductor 1002, the right-hand armature and back contact of relay 1008, the left-hand armature and contact of relay 1056, conductor 1057, the front contact and outermost lower armature of relay 1013 to conductor 1060, right-hand winding of re-

lay 1014, conductor 1015, back contact and armature of relay 1016 to battery and ground. Relay 1014 becomes energized in this circuit and extends the ground on conductor 1060 through its left-hand winding, 70 its front contact and innermost left-hand armature to conductor 1061, thence through the back contact and innermost left-hand armatures of relays corresponding to 1014 in other senders such as 1020 to conductor 75 1062, winding of relay 1016 to battery and ground. Thus relay 1016 becomes energized in the locking circuit of relay 1014 and removing ground from conductor 1015 prevents the energization of other relays 80 corresponding to 1014 until this sender has been discharged.

A circuit is now established from ground, the innermost right-hand armature and front contact of relay 1014, conductor 1063, 85 conductor 961, through the corresponding contacts of switching device 915, conductor 962, corresponding contacts of switching device 909, conductor 963, conductor 430, right-hand armature and front contact of 90 relay 340, conductor 371, conductor 431, conductor 940, conductor 1064, winding of magnet 1007, to battery and ground. If as before described the hundreds digit had been three instead of four relay 340 would 95 not have been energized and the circuit just described would have been extended through the back contact of relay 340 and caused the energization of magnet 1006 instead of 1007 for operating the marker or switching device 1075. Magnet 1007 operates the switching device 1025. A circuit is also established from ground, middle right-hand armature and front contact of relay 1014, conductor 1024, conductor 966, corresponding contacts of the switching device 915, conductor 967, corresponding contacts of switching device 909, conductor 941, conductor 432, winding of magnet 412 to battery and ground. Magnet 412 becomes 110 energized in this circuit and prepares for the operation of switching devices 413, 414, 415, 416. A circuit is now established from ground, front contact and left-hand armature of magnet 412, conductor 433, conductor 1107, winding of relay 1108 to battery and ground. Relay 1108 connects ground to conductor 1102 to replace the ground supplied over conductor 1100 after relay 1101 becomes energized. Relay 1108 also 120 extends a ground connection through its right-hand armature to conductor 1103.

A circuit is also established from ground, front contact and outermost armature of relay 1014, conductor 1065, right-hand armature and front contact of relay 1047, conductor 1052, outermost lower armature and front contact of relay 1050, conductor 1066, corresponding contacts of switching device 1025, conductor 1021, conductor 964, con- 125 130

ductor 457, winding of magnet 405 to battery and ground. Magnet 405 becomes energized in this circuit and prepares for operation of switching devices 407, 408, 409 and 410. A circuit is now closed from ground, front contact and right-hand armature of magnet 412, conductor 458, armature and front contact of magnet 405, conductor 459, conductor 965, conductor 1022, corresponding contacts of switching device 1025, conductor 1011, outermost left-hand armature and front contact of relay 1014, conductor 1012, lower armature and front contact of relay 1059, conductor 1013, corresponding contacts of switching device 1025, conductor 1030, conductor 968, conductor 464, normal contacts of the inner right-hand armature of magnet 403, winding of magnet 403 to battery and ground. Magnet 403 becomes energized in this circuit and operates switching devices 415, 409 thereby connecting the called line No. 1427 to trunk 418 and thence to trunk 118.

During the operation of magnet 403 there is an instant when the inner right-hand armature of magnet 403 is connected through its alternate contact to its normal contact so that the grounded conductor 464 is connected through the corresponding contact of switching device 415 to conductor 419, thence through conductor 1113 to the winding of cut-off relay 1101. Cut-off relay 1101 being quick to act attracts its armatures and becomes locked in a circuit from ground, front contact and right-hand armature of relay 1108, right-hand armature and front contact of relay 1101, winding of relay 1101 to battery and ground. Through the movement of its left-hand armatures, relay 1101 cuts off the subscriber's line from control of the sender and battery and ground are supplied to the calling subscriber through the windings of supervisory relay 1114. Relay 1114 thereupon establishes a holding circuit for relay 1108 which is maintained until the calling subscriber replaces his receiver on the switchhook. The initial energizing circuit of relay 1108 is broken upon the subsequent deenergization of magnet 412 as hereinafter described.

The circuit of the impulse relay 1001 now being opened, this relay becomes deenergized and causes relay 1008 to become energized for an instant. Thereupon the circuit for relay 1014 is opened at the right-hand armature and contact of relay 1008 and this relay retracts its armatures. Shortly after the deenergization of impulse relay 1001, holding relay 1003 becomes deenergized so that all of the relays which have been up to this time locked to ground on conductor 1004 and the extension 1041 of conductor 1004 now become deenergized. Thus magnet 1007, all of the counting relays, relays 1050 and 1047 become deenergized, also magnets

904 and 912 become deenergized and retract their armatures disconnecting the sender from the trunk and restoring the common apparatus to normal. Magnets 405 and 412 also become deenergized and leave magnet 70 403 holding the connection through the operated switching devices 415 and 409.

It should be noted at this point that at the time magnet 412 was energized a circuit was established in parallel therewith for relay 75 1109 extending through conductor 1111 to the right-hand winding of relay 1109 to battery and ground causing this relay to become energized. Thereupon the third conductor 461 of the called line 1427 is connected through corresponding contacts of switching device 409 to conductor 457, thence through the corresponding contacts of switching device 415 to conductor 420, conductor 1110, the right-hand armature and front contact of relay 1109, normal contacts of the innermost right-hand armature of relay 1112, right-hand winding of relay 1112 to battery and ground. If the line 80 1427 is idle at this time, this circuit is ineffective and upon the removal of ground from conductor 432 and the consequent deenergization of relay 1109, conductor 1110 is connected to ground at the back contact and innermost right-hand armature of relay 1109 and cutoff relay 401 is energized over the circuit just described to mark the called line as busy.

Called line busy.

100

Let us assume first, however, that line 1427 is busy. This being the case, a ground potential will be found on conductor 461 and this being connected by the circuit described to the right-hand winding of relay 1112, this relay will attract its armature and lock up in a circuit from ground, front contact and right-hand armature of relay 1108, right-hand armature and front contact of relay 1101, conductor 1113, outermost right-hand armature and front contact of relay 1109, innermost right-hand armature and front contact of relay 1112, right-hand winding of relay 1112 to battery and ground. This ground connection will also be extended through the alternate contact of relay 1112 to the left-hand winding of relay 1109 to maintain this relay energized after its original energizing circuit is opened. Again this ground connection will be extended from conductor 1113, through the outer right-hand armature and front contact of relay 1109 to the left-hand winding of relay 1115 to battery and ground to operate this relay and cut off the called line from the windings of supervisory relay 1116. A busy tone circuit is now established from a source BT of busy tone, the front contact and middle right-hand armature of relay 1112, condenser 1117, 110 115 120 125 130

right-hand winding of supervisory relay 1116 to battery and ground. Through induction, this busy tone is transmitted through condensers 1119 and 1120 to the calling line to notify the subscriber there that the called line is busy. If the calling subscriber now replaces the receiver on its hook, he will deenergize calling supervisory relay 1114 which by removing ground from the winding of relay 1108 will allow this relay to become deenergized after a short interval. When this happens the ground is removed from conductor 1103 and conductor 1102. The removal of ground from conductor 1102 causes the deenergization of magnets 303, 203 and 103 which severs the connection by restoring the switching devices 309, 315, 209, 215, 109, 115. This also removes the ground from the third wire to deenergize the cutoff relays 301, 201 and 101, and thus the calling end of the connection is entirely restored to normal. The removal of ground from conductor 1103 releases relays 1101, 1112, 1109 and 1115 and at the same time causes the deenergization of relay 320 whereby trunk 318 again becomes available for use. The removal of ground from conductor 1113 through the deenergization of relay 1108 allows the magnet 403 to become deenergized and this magnet restores switching devices 415 and 409 to normal so that the connection at this point is restored to normal.

Called line idle.

Let us now assume that line No. 1427 is idle. In this case the relay 1112 does not become energized as hereinbefore described, but while 1109 is still energized a connection from ground is extended over conductor 1113 through the outer right-hand armature and front contact of relay 1109 to the left-hand winding of relay 1115 to battery and ground so that relay 1115 becomes energized and is immediately locked to conductor 1113 through the outermost right-hand armature of relay 1112. When relay 1109 becomes deenergized, as heretofore described, a circuit is established from ground, back contact and outer left-hand armature of relay 1109, front contact and outer left-hand armature of relay 1115, conductor 1121, conductor 421, corresponding contacts of switching device 415, conductor 422, corresponding contacts of switching device 409, conductor 423 through the loop of substation 424, conductor 425, corresponding contacts of switching device 409, conductor 426, corresponding contacts of switching device 415, conductor 427, conductor 1122, inner left-hand armature and front contact of relay 1115, inner left-hand armature and back contact of relay 1109, left-hand winding of relay 1112 to a source of ringing current 1123. The current passing through this circuit is in- sufficient to cause the energization of relay 1112 until the subscriber at substation 424 removes his receiver from its switchhook. Thereupon relay 1112 becomes energized and opening the holding circuit of relay 1115, 70 allows this relay to deenergize to cut off the ringing current from the called subscriber's line and to connect said line to the windings of calling supervisory relay 1116. The deenergization of relay 1115 opening the energizing circuit for relay 1112 allows this relay now to become deenergized and the circuits are in condition to permit conversation to proceed. 75

If at the end of a conversation the called subscriber should hang up first, relay 1116 would become deenergized but nothing else would happen since the connection is maintained through the energization of the calling supervisory relay 1114. When the calling subscriber hangs up he causes the deenergization of relay 1114. The circuit of relay 1108 is now opened and this relay causes the restoration of the entire connection as hereinbefore described. If the calling subscriber hangs up first, ground is removed from the winding of relay 1108, and this relay after an interval becomes deenergized, but relay 1116 still remaining energized maintains the ground on conductor 1113 so that cutoff relay 1101 remains in its energized position, thus holding the connecting devices of Fig. 4 energized, but allowing the connecting devices of Figs. 1, 2 and 3 to be restored to normal. Thereafter, when the called subscriber at substation 424 replaces his receiver and deenergizes relay 1116, the switching device of Fig. 4 will be restored to normal. 90

What is claimed is:

1. In a telephone system, a number of separate selective switches each having contacts and bars cooperating with each other to operate said contacts, lines incoming to each of said switches, numerical groups of lines each group comprising a plurality of numerically equivalent lines outgoing from said switches, each switch having a number of link circuits cooperating with said contacts to extend said incoming lines to said outgoing lines, a plurality of recording mechanisms for storing designations each arranged to cause the operation of said switches to select any one of said numerical groups of lines, and means for selecting an idle line in the selected group. 105
2. In a telephone system, a number of separate selective switches each having contacts and intersecting bars cooperating with each other to operate said contacts, lines incoming to each of said switches, numerical groups of lines each group comprising a plurality of numerically equivalent lines outgoing from said switches, each switch having a number of link circuits cooperating with said contacts to extend said incoming lines to said outgoing lines, a plurality of recording mechanisms for storing designations each arranged to cause the operation of said switches to select any one of said numerical groups of lines, and means for selecting an idle line in the selected group. 110
3. In a telephone system, a number of separate selective switches each having contacts and intersecting bars cooperating with each other to operate said contacts, lines incoming to each of said switches, numerical groups of lines each group comprising a plurality of numerically equivalent lines outgoing from said switches, each switch having a number of link circuits cooperating with said contacts to extend said incoming lines to said outgoing lines, a plurality of recording mechanisms for storing designations each arranged to cause the operation of said switches to select any one of said numerical groups of lines, and means for selecting an idle line in the selected group. 115
4. In a telephone system, a number of separate selective switches each having contacts and intersecting bars cooperating with each other to operate said contacts, lines incoming to each of said switches, numerical groups of lines each group comprising a plurality of numerically equivalent lines outgoing from said switches, each switch having a number of link circuits cooperating with said contacts to extend said incoming lines to said outgoing lines, a plurality of recording mechanisms for storing designations each arranged to cause the operation of said switches to select any one of said numerical groups of lines, and means for selecting an idle line in the selected group. 120
5. In a telephone system, a number of separate selective switches each having contacts and intersecting bars cooperating with each other to operate said contacts, lines incoming to each of said switches, numerical groups of lines each group comprising a plurality of numerically equivalent lines outgoing from said switches, each switch having a number of link circuits cooperating with said contacts to extend said incoming lines to said outgoing lines, a plurality of recording mechanisms for storing designations each arranged to cause the operation of said switches to select any one of said numerical groups of lines, and means for selecting an idle line in the selected group. 125
6. In a telephone system, a number of separate selective switches each having contacts and intersecting bars cooperating with each other to operate said contacts, lines incoming to each of said switches, numerical groups of lines each group comprising a plurality of numerically equivalent lines outgoing from said switches, each switch having a number of link circuits cooperating with said contacts to extend said incoming lines to said outgoing lines, a plurality of recording mechanisms for storing designations each arranged to cause the operation of said switches to select any one of said numerical groups of lines, and means for selecting an idle line in the selected group. 130

- with said contacts to extend said incoming lines to said outgoing lines, a recording mechanism common to said switches for storing the designations of wanted lines, 5 said mechanism being arranged to cause the operation of any one of said switches to select a desired numerical group of lines, and means for selecting the first idle line in the selected group.
- 10 3. In a telephone system, a number of separate selective switches each switch having sets of coordinate bars, each bar of one set cooperating with each bar of another set, lines incoming to each of said switches, 15 numerical groups of lines each group comprising a plurality of numerically equivalent lines outgoing from said switches, each switch having a number of link circuits for extending said incoming lines to said outgoing lines, a plurality of recording mechanisms for storing designations, each arranged to cause the operation of the cooperating bars of said switches to establish 20 connections through said switches to a desired numerical group of lines, and means for selecting an idle line in the desired group.
4. In a telephone system, a number of 30 selective switches, incoming lines, numerical groups of lines each group having a plurality of numerically equivalent lines outgoing from said switches, each switch having link circuits for interconnecting incoming lines with outgoing lines, line bars for said 35 incoming and outgoing lines and link bars for said link circuits, said bars cooperating with each other to establish connections through said switches, and a plurality of recording mechanisms for storing designations each arranged to cause the operation of said switches to select any one of said 40 numerical groups of lines.
5. In a telephone system, selective switches, incoming lines, numerical groups 45 of lines each group including a plurality of numerically equivalent lines outgoing from said switches, each switch having link circuits for interconnecting incoming lines with outgoing lines, line bars for said incoming 50 and outgoing lines and link bars for said links, a recording mechanism for storing designations arranged to cause the operation of an incoming line bar, an outgoing line bar and a link bar of any switch to determine 55 the selection of a desired group of outgoing lines, and means for causing the release of the line bars and for holding the link bar operated to maintain the connection, the successive operation of a single 60 line bar serving to establish a plurality of coexisting connections.
6. The combination in a telephone system 65 of a number of separate selective switches each having contacts and bars cooperating with each other to operate said contacts, lines incoming to each of said switches, a number of different numerical groups of lines outgoing from said switches each group consisting of a plurality of numerically equivalent lines, each switch having a number of links cooperating with said contacts to extend the incoming lines to the outgoing lines, a plurality of recording mechanisms set by impulses to record wanted designations, each mechanism arranged to cause the operation 70 of said switches to select a numerical group of lines, and means for choosing an idle line in the selected group.
7. The combination in a telephone system 75 of subscribers' lines, a number of separate selective switches each having sets of intersecting bars, means for extending said lines to said switches, numerical groups of lines each group comprising a plurality of numerically equivalent lines outgoing from said switches, each switch having a number of link circuits rendered effective by the operation of said bars to extend said subscribers' lines to said outgoing lines, a plurality of recording mechanisms for storing designations, an automatic switch for extending a calling subscriber's line to an idle one of said mechanisms, said mechanism serving to cause the operation of said switches to select any one of said numerical groups of lines, and means for choosing an idle line in the selected group.
8. The combination in a telephone system 80 of a group selecting stage comprising a number of separate selective switches each having rows of contacts and intersecting bars cooperating with each other to operate said contacts, lines incoming to said switches, numerical groups of lines each group having a plurality of numerically equivalent lines outgoing from said switches, each switch having a plurality of equivalent link circuits cooperating with said contacts to extend said incoming lines to said outgoing lines, a plurality of recording mechanisms 85 for storing the designations of wanted lines, each mechanism arranged to cause the operation of any switch at said stage to select a desired numerical group of outgoing lines, and means for automatically seizing an idle 90 line in the selected group.
9. The combination in a telephone system 95 of a series of group selecting stages each stage comprising a number of separate selective switches, each switch having contacts and bars cooperating with each other to operate said contacts, lines incoming to the switches at the first stage, numerical groups of lines each group comprising a plurality of numerically equivalent lines outgoing from the switches at each stage and incoming to the switches at the succeeding stage, each switch having a number of link circuits coacting with said contacts to extend the incoming lines to said outgoing lines, a plural- 100

- ity of recording mechanisms at each stage for storing designations, each mechanism arranged to cause the operation of the switches at the corresponding stage to select 5 any of said numerical groups of lines outgoing from such switches, and means for selecting an idle line in the selected group.
10. The combination in a telephone system of a series of selective switches each having 10 contacts and bars cooperating with each other to operate said contacts, lines incoming to the first of said switches, a group of numerically equivalent lines outgoing from each of said switches and incoming to the 15 succeeding switch, each switch having a number of link circuits cooperating with said contacts to extend said incoming lines to said outgoing lines, a recording mechanism for each of said switches for storing 20 designations, each recording mechanism serving to prepare its associated switch for operation to select a numerical group of outgoing lines, and means responsive to the seizure of each recording mechanism for 25 completing the operation of the preceding switch.
11. In combination, a plurality of separate selective switches each having a plurality of sets of cooperating bars and a field of 30 contacts, an incoming trunk multiplied to appear in contacts of all of said switches, trunks outgoing from said switches, and means for operating a plurality of bars at any one of said switches to extend said incoming trunk to one of said outgoing trunks.
12. In combination, a plurality of separate selective switches each having a plurality of sets of intersecting bars and a field of 40 contacts, a plurality of incoming trunks each multiplied to appear in contacts of all of said switches, trunks outgoing from said switches, and means for operating a plurality of bars at any one of said switches to extend one of said incoming trunks to one of said outgoing trunks.
13. The combination in a telephone system of a plurality of separate selective switches each having two sets of cooperating bars and a field of contacts, an incoming trunk multiplied to appear in contacts of all of said switches, trunks outgoing from said switches, and a recording mechanism serving to cause the operation of the bars at 50 any one of said switches for extending said incoming trunk to one of said outgoing trunks.
14. The combination in a telephone system of a plurality of separate selective switches each having a plurality of sets of cooperating bars and a field of contacts, an incoming trunk multiplied to appear in contacts of all of said switches, a group of trunks outgoing from each switch each 60 group leading in a different numerical di- rection, each switch having a number of link circuits cooperating with said contacts to extend the incoming trunk to said outgoing trunks, and means for operating a plurality of bars at any one of said switches 70 for engaging said contacts and link circuits.
15. The combination in a telephone system of a plurality of selective switches each having a plurality of sets of cooperating bars and a field of contacts, an incoming 75 trunk multiplied to appear in contacts of all of said switches, a group of trunks outgoing from each switch, each group leading in a different numerical direction, a number of recording mechanisms, means for associating a recording mechanism with all of said switches, and means dependent upon the designation recorded for causing the operation of the bars at the particular switch having access to the group of outgoing 80 trunks leading in the corresponding numerical direction.
16. The method of establishing a connection in a telephone system which comprises extending a calling subscriber's line to a trunk line, seizing and operating a sender associated with said trunk line, seizing a sender associated with a second trunk line in response to the operation of the first sender, thereupon extending said first trunk line to said second trunk line, operating said second sender, seizing a third sender associated with a third trunk line in response to the operation of the second sender, extending said second trunk line to said third trunk line, operating said third sender and extending said third trunk line to a called subscriber's line, said extending, operating and seizing being accomplished in response to dialing 90 impulses.
17. The method of establishing a connection in a telephone system which comprises extending a calling subscriber's line to a trunk line, seizing and operating a sender associated with said trunk line, seizing a second sender associated with a second trunk line in response to the operation of the first sender, extending said first trunk line to said second trunk line in response to the seizure of said second sender, operating said second sender, seizing a third sender associated with a third trunk line in response to the operation of said second sender, extending said second trunk line to said third trunk line, operating said third sender and extending said third trunk line to a called subscriber's line.
18. In a telephone system, multigroup connector switches having coordinate bars for operating the same, means for extending connections to said switches, means common to said switches for selecting said switches in accordance with the value of the digit used in thus extending said connections and other means common to said 110 115 120 125 130

switches for selecting a particular group in said selected switch in accordance with the character of said digit.

19. In a telephone system, coordinate 5 multigroup crossbar connector switches, means for extending connections to said switches, means for selecting said switches in accordance with the value of the digit

used in thus extending said connections, and means for selecting a particular group in 10 said selected switch in accordance with the character of said digit.

In witness whereof, I hereunto subscribe my name this 20th day of December A. D. 1921.

CHARLES L. GOODRUM.
